COUNTER CONSTRUCTION

Fred C. Kuenzie, Muskegon Heights, Mich., assignor to The Shaw-Walker Co., Muskegon, Mich., a corporation of Michigan

Application June 26, 1946, Serial No. 679,444

10 Claims. (Cl. 312—107)

1

This invention relates to improvements in combined sectional filing cabinets and office counters of the kind adapted for use in business offices to form a division between the reception space and the working space. A counter for this purpose also serves as a convenient place for filing records which must be referred to in connection with the business which is carried on over the counter.

Heretofore it has been the practice to make such counters by assembling standard filing units into a battery by bolting each filing unit to the next through holes near each corner of the side walls of the units. A prefabricated decorative facing is then bolted to the back of the battery and a prefabricated top is applied to the top of the battery so that the joints between the individual units are concealed from public view.

Since the requirements of different businesses are seldom the same as to the length of counter required, the kind and number of records to be housed, etc., the manufacturer of the tops and back facings for the counters has been on a custom-built basis which has made them expensive to manufacture and difficult to install and requiring a preliminary set up at the factory before delivering it to the customer.

The principal object of this invention is to provide a battery of standard filing cabinets with improved means including prefabricated back, end and top facing panels connecting said filing cabinets together in alignment to form a counter of the kind above described.

A further object is to construct the tops and back facings in standard size units which can be manufactured in quantity and installed on counters of various lengths with a minimum of effort by one man and in no case requiring more than a single short section to be made to measure.

Another object is to provide a means at the end of a counter for compensating for small differences in dimension between the length of the counter and the top and facing members which are applied to it.

Still another object is to eliminate the necessity for the use of bolts or screws to fasten the facing panels and tops to the filing units thus avoiding mutilating the filing units and making it possible to re-arrange or re-use the filing units in any way desired due to changed requirements.

The invention may best be understood by reference to the accompanying drawings, in which:

Figure 1 is a perspective view from the front and side of an office counter constructed in accordance with my invention.

Figure 2 is a view similar to Figure 1, with a

2

portion of the side facings and cover removed from the battery of filing units.

Figure 3 is a perspective view from the rear of the counter shown in Figure 1.

Figure 4 is an enlarged fragmentary view in perspective, showing details of a connecting clip for holding the bases of adjacent filing units together.

Figure 5 is a perspective view in vertical section taken transversely through the counter to show the connecting means for adjacent file units.

Figure 6 is a fragmentary detail view in perspective showing the supporting devices for the side panels.

15 Figure 7 is an enlarged fragmentary plan view of the parts shown at the top of Figure 6.

Figure 8 is an enlarged detail perspective view of the parts shown at the top of Figure 6, but with the connecting bolt removed.

20 Figure 9 is a fragmentary view in perspective, of one of the end panels, with parts broken away to show the adjusting devices therefor.

Figure 10 is a fragmentary view in perspective showing details of the means for connecting adjacent sections of the counter cover.

25 Figure 11 is an enlarged detail section showing the meeting edges of adjacent cover sections in separated position ready for insertion of an aligning spline, and

30 Figure 12 is an enlarged detail section of a connecting latch for adjacent cover sections.

Referring to details of the embodiment of my invention shown in the drawings, a counter indicated generally at 10 consists of a plurality of 35 standard metal filing units indicated generally at 11, 11 in Figure 2 which are secured together in side by side alignment and provided with a sectional counter top indicated generally at 12, fitting over and along said filing cabinets, and are 40 also provided with a sectional facing consisting of a plurality of facing panels 13 secured along the rear or closed ends of the filing cabinets, and end facing panels 14, 14 to complete the counter at opposite ends thereof.

45 As will be seen from Figures 1 and 2 the facing panels 13, when assembled, form the front of the finished counter while the drawers 15, 15 of the filing units 11, 11 are exposed at the rear of the counter for ready access by employees when desired.

As shown in Figure 3 an open frame section 16, having top, sides and a rear wall, may be inserted in the battery to form a knee-hole space, opening toward the rear of the counter, when desired.

It will also be manifest from Figure 3 that the

individual filing units may be of different widths. For instance, as shown in the latter figure the units to the left of the knee-hole frame 16 are of greater width than those to the right of said knee-hole frame.

The individual filing units and the knee-hole frame are first moved into their intended positions, and the adjacent filing units are set down over U-shaped connecting clips 17, 17 as indicated in Figure 5. Each of these clips are formed of sheet metal bent upwardly at each end to form a pair of spaced lugs 18, 18 having inwardly and upwardly tapered outer faces 19, 19, and with an intermediate flanged portion extending slightly beyond said lugs to form a shorter flange or 15 lug 20.

The bottom wall 22 of each filing unit 11 is provided with a plurality of receiving slots 23 of such shape and arrangement as to fit over each pair of tapered lugs 18, 18 at one end of a connecting clip 17 and said slots being of sufficient width to receive the outer face of the shorter, intermediate lug 20 snugly therein. Said lug is preferably inclined inwardly toward the clip, so that the tapered lugs 18, 18 and the inclined lug 20 will be 25 readily guided into its receiving slot.

The receiving slots 23 in the bottom walls of the filing units are disposed at uniform distances from the sides of said units and in alignment with each other so that when a pair of adjacent filing 30 units are fitted over one of the connecting clips 17, the units will be automatically positioned in closely fitting, abutting relation and in precise alignment with each other (see Figure 5).

In practice I prefer to connect each pair of units with two connecting clips 17, one near the front and the other near the rear of the counter, but one set of clips may often be sufficient for the purpose.

The upper ends of the filing units may be secured in side by side relation by means of bolts 25 and wing nuts 26 which may be passed through registering holes in the side walls of the units as shown in Figure 5. Such bolts and wing nuts are readily accessible for attachment through the top drawer openings of the filing units. The knee-hole frame 16 may be similarly fastened to the adjacent filing units.

After the several filing units making up the battery have been fastened together in proper position and alignment, the decorative facing panels 13, 13 may be assembled along the rear of the battery to form the front of the counter. The facing panels 13 are preferably of standard length, excepting for one section which is cut to proper length to fill out the length of the battery, when necessary. Each of said facing panels is provided with a horizontal channel shaped spacing web 30, along its top, formed of sheet metal with one upright flange 31 secured along the inner face of the panel and with its opposite upright flange or bearing element 32 terminating in a horizontal flange or bearing element 33, adapted to fit over the adjacent upper corner of the filing unit battery as shown in Figure 6. The 60 horizontal spacing webs terminate short of the ends of their respective panels to accommodate vertical spacing webs as will presently appear.

Each panel 13 also has a lower spacing web 35 with a downwardly extending outer flange 36 secured along the inner face of the panel, and an inner downwardly extending flange 37 adapted to engage the rear face of the filing unit battery near the bottom thereof, as shown in Figure 6. In the form shown, the facing panels 13 terminate 70

a few inches above the floor surface, in offset relation to a base member or mop strip 39 disposed directly along the bottom of the battery, thus leaving a toe space along the floor.

5 The meeting edges of abutting facing panels 13 are provided with similar upright channel shaped webs 40, 40 shown in Figure 7 which are almost flush with the panel edges and are adapted to be secured together by through-bolts and wing nuts 41, 42 near the top and bottom of the assembly, where the bolts and wing nuts are readily accessible by hand.

The upright spacing webs 40, 40 each have terminal inner flanges 43 which bear against the rear wall of the filing unit battery and fit between the adjacent ends of the upper and lower horizontal spacing webs 30, 35, respectively. The facing panels are held in place on the battery by means of U-shaped metal straps 45 which are made of proper width to fit flatwise across the top of the filing unit battery, with a depending flange 46 engaging the upper corner of the filing unit at the rear of the counter and with depending flanges 47 having a notched central portion 48 therebetween adapted to fit over the upper ends of the two vertical spacing webs 40, 40.

The depending flanges 47 of the locking strap 45 also fit in clamping engagement over an upright bearing element of the spacing webs at the 30 upper corner of each facing panel. In the form shown herein, each inner flange 43 of an upright spacing web 40 abuts an upright flange 32 of an upper horizontal spacing web 30 and a rectangular sheet metal reenforcing strip 49 overlies and connects said flanges so that said flanges and reenforcing strip together form in effect a continuous upright bearing element for engagement against the rear face of the filing unit battery when the retaining strap 45 is in assembled relation with its flanges 47 engaging the reenforcing strip 49, as shown in Figures 6 and 7.

The upright meeting edges of adjacent facing panels 13 are held in precise alignment with each other by means of upright sheet metal splines 50 which are inserted in open slots 51, 51 formed by inwardly offset flange portions 52, 52 of the upright webs 40, 40 as shown in Figure 7.

In the form shown each spline 50 is provided with a terminal flange 53 at its upper end to form a stop for said spline when it is fully inserted and also to provide means for readily removing the spline when the parts are to be disassembled.

Means are also provided for retaining the base member or mop strip 39 in place, herein consisting of a plurality of L-shaped clips 60 mounted on the under surface of the lower horizontal spacing web 35 and spaced from the inner terminal flange 37, each of said clips having a thumb screw 61 threaded therethrough adapted to hold the base member 39 in position along the floor and against the rear face of the filing unit battery.

Each end of the counter is provided with an end facing panel 70 which is generally similar in construction to the individual front panels 13, 13 excepting that the front and rear corners are rounded. The front corner of each end panel is provided with a rounded terminal flange 71 supported by a spacing web 72 and an integral laterally spacing web 73, as shown in Figure 9. The spacing web 72 is of substantially the same shape as the upright spacing web 40 of the adjacent front panel 13, to which the end panel is 75 connected as before, by bolt and wing nut 41, 42.

5

The laterally extending spacing web 73 forms the counterpart of the inner terminal flange 43 of spacing webs 40 on the panels 13, but in this instance extends laterally into engagement with the inner face of the end panel 70 to form a box-like support for the front corner of said end panel.

The rear corner of the end panel 70 is provided with an upright rounded terminal flange 75 which is secured to an upright angle strip 76, suitably connected to the corner of the outermost filing unit 15a substantially flush with the front face thereof, as shown in Figure 9.

In the form shown herein the angle strip 76 is provided with elongated horizontal slots 77, 78 near the top and bottom thereof to accommodate bolts 80, 80 passing through the terminal flange 75 which overlaps said angle strip 76. The bolts 80 are provided with wing nuts 81 which may be readily reached to secure the terminal flange 75 to said angle strip 76.

The end panel 70 also has an upper spacing web 83 similar to the upper spacing web 30 of the side panels 13, including an inner upright shoulder 84 and a horizontal flange 85 which rests on top of the adjacent filing unit 11.

Endwise adjustment of the parts may be provided in the lower spacing web of the end panel 70 by forming said lower spacing web of two telescopic sheet metal plates 86 and 87. One plate 86 may be provided with an elongated slot 88 in which a bolt 89 passing through thelapping plate 87 may have sliding adjustment. The plates 86 and 87 are fastened in proper adjusted position by a wing nut 90 on bolt 89.

It will be understood that in fitting the side panels 13 to the filing unit battery, one of the panels 13 is cut to approximately the proper length so that the upright web 40 will be substantially in registry with the end of the battery unit as shown in Figure 9.

The adjustment provided by bolts 80 and 89 will allow for minor errors in the length of the end panel 13 such as may occur when assembling devices of this kind. The flange 85 of the upper spacing flange 83 is long enough to provide supporting engagement on the top of the adjacent filing unit 11 in all permissible positions of adjustment of the end panel.

The cover or counter top indicated generally at 12 is made up of a plurality of end sections 95 and one or more intermediate sections 96. The end sections 95 may be identical, and where a plurality of intermediate sections are employed they may also be identical excepting in some instances one or more of said sections may require cutting to proper length for the final assembly.

The top sections 95 and 96 have a plurality of longitudinally extending channel shaped members 100, 100 secured along their bottom faces. In the form shown these reinforcing members are substantially U-shape in cross section with their upper flanges secured to the under face of their respective top sections so as to rest on the top of the filing unit battery. The intermediate 60 section or sections 96 are edged with a depending molding 101 along their front and rear edges, while the end sections 95, 95 each have a similar edge molding 102 continuing around one end thereof, thus providing a complete molding along the sides and ends of the counter.

A preferred construction of the end sections is shown in detail in Figures 11 and 12 wherein the top sections 95, 96 each include a sheet metal plate 105 to which is secured a suitable surfac-

6

ing material 106 of fabric composition or the like.

The edge moldings 101, 102 may be made of metal or plastic suitably secured along the margins of the metal plate 105 with its upper surface flush with the surfacing layer 106, as shown in Figure 10.

The meeting edges between proximate top sections are preferably furnished with upstanding metal flanges 107 connected to the sheet metal plate 105, the terminal edges of said flanges being flush with the top surface of the surfacing material 106.

As shown in Figure 11 the meeting edges of the cover sections 95, 96 thus are preferably maintained in precise horizontal alignment by a sheet metal spline 108.

Each plate section is provided with a transversely extending angle bar 110 having its top flange secured in outwardly facing position beneath the edge of the metal plate 105 of its respective top section, and a longitudinal strip 111 is fixed along the bottom of said last-named flange with its outer margin offset downwardly to form an elongated marginal slot 109 for receiving the spline 108 therein.

It will be understood that in assembling the top sections the spline 108 is inserted edgewise in the opposed slots of proximate top sections as the latter are pushed together.

Means for locking proximate top sections together consists of pivoted latch members 115 which are pivotally mounted on depending angle members 116 secured to the margins of the metal plates 105 of each section adjacent their ends, as shown in Figure 10. These latch members are adapted to project beyond the end of their respective top sections and carry a hook 117 at their outer ends which engages a pin 118 fixed to a depending angle bar 119 fixed to the proximate meeting top section immediately beneath the edge molding 101.

The arrangement is such that these latches 117 may be reached by a suitable tool 120 as shown in Figure 12, said tool having a socket adapted to fit over the pivoted end of the latch 117, to swing it downwardly into latching engagement with the pin 118 on the adjacent top section, thus detachably securing the adjacent top sections together.

It will be observed that when the cover is in assembled position on the top of the filing unit battery, said cover rests on the connecting straps 45 to hold the latter in place, usually requiring no other securing means than the weight of the counter top alone.

From the above description it will now be understood that my improved counter construction permits quick and easy installation of office counters of varying sizes and capacities, varying 60 with the space available and the particular requirements of the installation. The main parts consisting of the facing panels and top sections may be prefabricated to standard limits suitable for a wide variation in counter lengths and at the most requiring the cutting of only one facing panel and one cover section to a specific length. Adjustment is also provided for the end panel sections to allow for minor variations or errors in the file assembly and the cutting of the special sections to proper length.

It will also be understood that the facing panels and cover sections are demountable so that they can be re-employed in other installations when desired.

Although I have shown and described certain

embodiments of my invention, it will be understood that I do not wish to be limited to the exact construction shown and described, but that various changes and modifications may be made without departing from the spirit and scope of the invention as defined in the appended claims.

I claim:

1. In a composite counter structure, a plurality of filing cabinet units of uniform height and length, means for fastening said units together in side-by-side abutting engagement to form a continuous battery of such units, facing panel sections detachably mounted on the rear face of said battery, each consisting of an upright plate having marginal spacing webs including angle members with horizontal and vertical bearing elements fitting along the upper edge of said battery for supporting engagement on the top and rear of the latter, and means for detachably securing said panel sections to said battery including metal straps each having depending lugs at opposite ends to span the top of said battery from front to rear thereof, with the lugs at one end of said strap fitting over the upright elements of said angle members to hold said spacing webs in lateral bearing engagement with the upright rear wall of said battery.

2. In a composite counter structure, a plurality of filing cabinet units of uniform height and length, means for fastening said units together in side-by-side abutting engagement to form a continuous battery of such units, facing panel sections detachably mounted on the rear face of said battery, each consisting of an upright plate having marginal spacing webs including angle members with horizontal and vertical bearing elements fitting along the upper edge of said battery for supporting engagement on the top and rear of the latter, and means for detachably securing said panel sections to said battery including metal straps each having depending lugs at opposite ends to span the top of said battery from front to rear thereof, with the lugs at one end of said strap fitting over the upright elements of said angle members to hold said spacing webs in lateral bearing engagement with the upright rear wall of said battery, and cover means arranged to rest along the top of said battery and in engagement with said straps to hold the latter in place.

3. In a composite counter structure, a plurality of filing cabinet units of uniform height and length, means for fastening said units together in side-by-side abutting engagement to form a continuous battery of such units, facing panel sections detachably mounted on the rear face of said battery, each consisting of an upright plate having marginal spacing webs including angle members with horizontal and vertical bearing elements fitting along the upper edge of said battery for supporting engagement on the top and rear of the latter, and means for detachably securing said panel sections to said battery including metal straps each having depending lugs at opposite ends to span the top of said battery from front to rear thereof, with the lugs at one end of said strap fitting over the upright elements of said angle members adjacent the upper corners of proximate panel sections to hold said spacing webs in lateral bearing engagement with the upright rear wall of said battery.

4. In a composite counter structure, a plurality of filing cabinet units of uniform height and length, means for fastening said units together in side-by-side abutting engagement to form a

continuous battery of such units, facing panel sections detachably mounted on the rear face of said battery, each consisting of an upright plate having marginal spacing webs including angle members with horizontal and vertical bearing elements fitting along the upper edge of said battery for supporting engagement on the top and rear of the latter, means for detachably securing said panel sections to said battery including metal straps each having depending lugs at opposite ends to span the top of said battery from front to rear thereof, with the lugs at one end of said strap fitting over the upright elements of said angle members adjacent the upper corners of proximate panel sections to hold said spacing webs in lateral bearing engagement with the upright rear wall of said battery, and cover means arranged to rest along the top of said battery and in engagement with said straps to hold the latter in place.

5. In a composite counter structure, a plurality of filing cabinet units of uniform height and length, means for fastening them together in side-by-side abutting alignment to form a continuous battery of such units, facing panel means detachably mounted on the rear face of said battery consisting of a plurality of panel sections, each having horizontal spacing webs along their upper and lower margins, the upper spacing webs including angle members with horizontal and vertical bearing elements adapted to fit along the upper edge of said battery for supporting engagement on the top and rear of the latter, said panel sections also having upright spacing webs along their ends adapted for connection with similar webs of proximate panel sections, and means for detachably securing said panel sections to said battery including metal straps each having depending lugs at opposite ends arranged to span the top of said battery from front to rear thereof, with the lugs at one end of said strap fitting over the upright elements of spacing webs of proximate panel sections to hold said spacing webs in lateral bearing engagement with the rear upright wall of said battery.

6. In a composite counter structure, a plurality of filing cabinet units of uniform height and length, means for fastening them together in side-by-side abutting alignment to form a continuous battery of such units, facing panel means detachably mounted on the rear face of said battery consisting of a plurality of panel sections, each having horizontal spacing webs along their upper and lower margins, the upper spacing webs including angle members with horizontal and vertical bearing elements adapted to fit along the upper edge of said battery for supporting engagement on the top and rear of the latter, said panel sections also having upright spacing webs along their ends, adapted for connection with similar webs of proximate panel sections, and means for detachably securing said panel sections to said battery including metal straps each having depending lugs at opposite ends arranged to span the top of said battery from front to rear thereof, with the lugs at one end of said strap being bifurcated to span the upper ends of the upright spacing webs of proximate panel sections at their point of juncture, and said lugs also fitting over upright elements of said angle members adjacent the corners of said proximate panel sections to hold said spacing webs in lateral bearing engagement with the upright rear wall of said battery.

7. In a composite counter structure, a plurality

of filing cabinet units of uniform height and length, means for fastening them together in side-by-side abutting alignment to form a continuous battery of such units, facing panel means detachably mounted on the rear face of said battery consisting of a plurality of panel sections, each having horizontal spacing webs along their upper and lower margins, the upper spacing webs including angle members with horizontal and vertical bearing elements adapted to fit along the upper edge of said battery for supporting engagement on the top and rear of the latter, said panel sections also having upright spacing webs along their ends, adapted for connection with similar webs of proximate panel sections, means for detachably securing said panel sections to said battery including metal straps each having depending lugs at opposite ends arranged to span the top of said battery from front to rear thereof, with the lugs at one end of said strap being bifurcated to span the upper ends of the upright spacing webs of proximate panel sections, and said last-named lugs also fitting over upright elements of the angle members adjacent the corners of said proximate panel sections to hold said spacing webs in lateral bearing engagement with the adjacent upright wall of said battery, and cover means arranged to rest along the top of said battery and projecting beyond the upper margins of said panel sections, said panel means being disposed in engagement with said straps to hold the latter in place.

8. In a composite counter structure, a plurality of filing cabinet units of uniform height and length, means for fastening said units together in side-by-side abutting engagement to form a continuous battery of such units, facing panel sections detachably mounted on the rear face of said battery, each consisting of an upright plate having horizontal spacing webs along their upper and lower margins, means for detachably securing the upper spacing webs to said battery, said panel sections terminating in spaced relation above the bottom of said battery, a sectional base plate adapted for engagement with the outer face of said battery adjacent the floor, and means for holding said sectional base plate in place consisting of a plurality of screw devices mounted on the lower horizontal spacing webs, extending into adjustable engagement with said base plate and accessible from beneath said horizontal spacing web.

9. In a counter assembly, an elongated battery of filing cabinets in alignment with each other,

5 sectional rear facing panels, means for detachably connecting said panels along the rear face of said battery including marginal spacing webs at opposite ends thereof, and end facing panels each having corner portions at each end to form finished front and rear corners for the end of the counter structure, one of said corner portions having a marginal spacing web parallel with the main body portion of its respective panel for detachable connection to a corresponding spacing web of the proximate rear facing panel, and the opposite corner portion of said end panel having telescopic adjustable connection with an extension member fixed to the front corner of the proximate filing cabinet.

10. In a counter assembly, an elongated battery of filing cabinets in alignment with each other, sectional rear facing panels, means for detachably connecting said panels along the rear face of said battery including marginal spacing webs at opposite ends thereof, and end facing panels each having corner portions at each end to form finished front and rear corners for the end of the counter structure, one of said corner portions having a marginal spacing web parallel with the main body portion of its respective panel for detachable connection to a corresponding spacing web of the proximate rear facing panel, and the opposite corner portion of said end panel having telescopic adjustable connection with an extension member fixed to the front corner of the proximate filing cabinet, and each of said end facing panels also having horizontal spacing webs along their upper margins adapted for supporting engagement with the top surface of the proximate filing cabinets in the various adjusted positions of said end facing panels whereby said end facing panels may be accommodated to minor variations in the length of said rear facing panels relative to the length of said filing cabinet battery.
